UNITED STATES PATENT OFFICE.

WILLIAM H. PALMER, OF PITTSBURGH, PENNSYLVANIA.

FORCED-DRAFT FURNACE.

Application filed October 22, 1921, Serial No. 509,582. Renewed August 15, 1924.

To all whom it may concern:

Be it known that I, WILLIAM H. PALMER, a citizen of the United States, and residing in the city of Pittsburgh, in the county of Allegheny and State of Pennsylvania, have invented or discovered a new, useful, and Improved Forced-Draft Furnace, of which the following is a specification.

My invention consists in certain new and useful improvements in forced draft furnaces, such, for instance as boiler furnaces.

The object which I have in view is the provision of improved means for supplying an artificial draft to the fuel bed, and for properly distributing the same. More particularly my invention is designed for use in connection with a closed grate structure which supports the fuel bed but does not permit the fuel or the products of combustion to pass down through the grate structure, the necessary air being supplied by artificial draft through openings in the grate surface.

For the purpose of properly distributing the artificial draft I provide a novel and improved air-chamber structure located beneath the grate and which is particularly adapted for the purpose above referred to, although the same may be advantageously used in connection with the ordinary spaced apart grate bars.

I also show a new and improved form of closed grate bar structure and assemblage of the same to constitute the closed fuel supporting platform or grate.

I also show a new and improved furnace construction in which various features of my invention are employed.

Other novel features of construction and arrangement of parts will appear from the following descriptions.

In the accompanying drawings, which are however merely intended to illustrate the principles of my present invention without limiting the scope of the latter to the construction shown, Fig. 1 is a sectional perspective showing a furnace fitted with the preferred form of my invention; Fig. 2 is a partial plan view of the same, some of the grate bars being removed to more clearly show parts; Fig. 3 is an enlarged perspective of one of the air-chambers, and Fig. 4 is an enlarged sectional view showing two grate bars superimposed over an air-chamber which is located in the furnace pit.

The following is a detailed description of the drawings;

A represents the front wall of the furnace provided with a plurality of spaced apart 60 pit doors 1, while 2 are the fuel doors, one of the same being preferably positioned above each of the pit doors.

B represents the bridge wall and C one of the side walls of the furnace. 65

The front and bridge walls are provided with horizontal flanges 3 which support the ends of the grate bars D, which bars, between the said supporting flanges, are provided with depending, vertical side walls 70 4. The tops 5 of said bars are horizontal except at the front where they are upwardly inclined toward the front wall A, as shown in Fig. 1.

The grate bars herein shown are similar 75 to the grate bars shown and described in Letters Patent of the United States No. 958,971, issued to me on May 24, 1910, except that in the present case the bottoms of the bars are shown open, the bars being 80 substantially inverted channels.

The top walls 5 of the bars are provided with apertures 6 in which are seated the cover plates 7, arcuate air spaces 8 being provided between the walls of the apertures 85 and said plates, as is more fully described in said Letters Patent.

The bars D are assembled in close proximity, the spaces between adjacent bars being filled with asbestos cement 9, or some 90 other refractory material.

To properly support the packing or filling 9, between the bars D, I prefer to provide a metal bar 10, which is preferably an inverted channel or V bar having its ends 95 suitably supported from the front wall and bridge wall by means of flanges or brackets, not shown but similar to the flanges 3 which support the ends of the grate bars D.

It is thus seen that the fuel is supported 100 on a substantially tight platform down through which the fuel or products of combustion can not pass, but up through which the air necessary for combustion is introduced by means of the openings 8. 105

E represents an air manifold which is connected to a fan or some other convenient source of artificial draft. Said manifold is shown in its preferred form—a duct or passageway underneath the floor of the pit 110 F and running transversely of the same near the bridge wall B.

At intervals vertical ducts 11 lead up from the said manifold into the interior of said pit, said ducts being alined between adjacent pit doors 1.

5 H represents the air-chamber members positioned in the pit F so as to receive the air from the ducts 11.

The preferred form of said air-chamber is that of a metal box of triangular shape 10 having its ends closed and having an open bottom which is placed over one of the ducts 11. Thus, as shown in Fig. 3, the boxes H have sides 12 formed by inclined plates whose upper ends are bent into a 15 vertical plane and bolted together forming a ridge flange 13. The ends of the box are formed of the triangular plates 14. One of said open bottom boxes is placed over each of the ducts 11, with the rear end of the 20 box flat against the bridge wall and its ridge extending up into, and preferably aiding in the support of the angle bar 10.

I is a brick partition wall built up from the floor of the pit to the angle bar 10, and 25 extending from the central front of the box H to the front wall of the pit. The wall I may also assist in supporting the bar 10. It is thus seen that the air-chamber H and the partition walls I divide the pit 30 into a plurality of compartments, access to which is obtained through the respective pit doors 1.

The side walls of each air-chamber H are provided with longitudinally elongated 35 air ports 15 which are closable by means of the shutters 16 slidably mounted in the guide plates 17 attached to the box. 18 represents operating rods having their inner ends attached to said shutters and their outer ends protruding through holes in the front wall of the furnace and looped to 40 form the handles 19. The shutters are opened by being moved toward the bridge wall, and when fully open the handles 19 impinge against the front wall of the furnace. To close or partially close said ports, 45 the handles are pulled outwardly, so that a protruding handle will remind the fireman that the corresponding air port is closed, or partially closed, as indicated by the degree of protrusion of the handle relative to the front wall of the furnace.

It is evident that when the ports in the 55 adjacent walls of a pair of adjacent air-chambers are open, the artificial draft will be supplied to the pit compartment defined between said chambers and the corresponding partition walls, and that the amount of said draft may be regulated by the adjustment of the port shutters; or the draft may be cut off from said compartment by moving said shutters into position to entirely close said ports.

Thus the draft may be admitted to the 60 portion of the grate platform over any

one or more pit compartments; may be regulated in regard to the same; or be entirely cut off in case that portion of the fire is to be cleaned. Thus one portion of the fire can be cleaned at a time, without materially cutting down the heating effect of the entire furnace.

The upwardly contracted form of the air chambers prevents the loss of draft area, and also obviates the possible accumulation 75 of dust which might filter down through the air openings in the grate bars, as the same will slide down the exterior walls of the chamber to the floor of the pit whence it may be removed through the pit doors.

I prefer to position the air escape ports at the opposite ends of the air chambers from the inlet ducts, thus preventing any dust which may enter the air chambers from reaching the ducts or manifold.

The apparatus is extremely simple and can readily be repaired when necessary.

Although, for the sake of clearness of illustration of the principles of my invention, I have minutely described the embodiment of the same shown in the drawings, I do not wish to limit myself thereby, but claim broadly:—

1. In a furnace, the combination of a fuel platform composed of closed grate bars, partition walls running from the front wall to the bridge wall, and from the bottom of the pit to the fuel platform, dividing the pit into a plurality of separate compartments, air chambers interposed in said partition walls and provided with ports communicating with the ash pit compartments on either side, valves for said ports, means for the individual operation of said valves from without the furnace, and means for supplying forced draft to said air chambers.

2. In a furnace, the combination of a forced draft fuel platform closed against the downward passage of fuel therethrough and comprised of a plurality of grate bars of inverted channel shape, said grate bars being provided with openings for the upward escape of air therethrough, vertical partitions running from the front wall to the bridge wall dividing the pit into a plurality of compartments which are roofed by the fuel platform, air chambers in said partitions, ports in the side walls of said air chambers communicating with the compartments on either side of the same, valves for said ports, means for the individual operation of said valves from without the furnace, and means for supplying forced draft to said air chambers.

3. In a furnace, the combination of a fuel platform composed of closed grate bars having openings for the upward passage of air, partitions running from the front wall to the bridge wall dividing the pit be-

neath the platform into a plurality of compartments, air boxes interposed in and forming parts of said partitions, said air boxes having upwardly converging side walls provided with ports communicating with the compartments at their sides, valves for said ports, means for the individual

operation of said valves from without said furnace, and means for supplying air blast to said boxes.

10

Signed at Pittsburgh, Pa., this 20th day of October, 1921.

WILLIAM H. PALMER.
